07-342

EX

OR D 605

Ch 605

N. P. Barnard Richardson's Design for a Banking's Store.

Patented 20. Oct. 1853.

Wes. 605

N. P. Richardson, of Portland, Me.
Letters Patent No. 605. Dated Oct. 25th, 1853.

The schedule referred to in these Letters Patent, and making part of the same.

To all persons to whom these presents shall come:

Be it known, that I, N. Putnam Richardson, of Portland in the County of Cumberland, and State of Maine, have invented or produced a new ornamental design for a cooking stove, and I do hereby declare that the same is described and represented in the following specification, and the accompanying drawings, letters, figures, and references thereto.

Of the said drawings, Figure 1, represents a perspective elevation of my said design exhibiting the side, end, front, and top of the stove.

Figure 2 is a horizontal section of the front plate and fire place door A, the same being taken through the middle of the latter.

Figure 3 is a vertical central and transverse section of the sill fire place door C.

Figure 4 is a vertical and transverse section of the side plate and door E, and the ornamental panel B.

Figure 5 is a horizontal and central section of the door F.

Figure 6 denotes a front view of that part of the front plate which is under the hearth H, the same being denoted at I in Figure 1.

In the drawings A, B, represent the front fire place doors; C, the side or end door of the fire place; E, an ash pit or oven door; F, the main oven door; G, the side hearth; H, the main hearth; K, K, the legs. a, is the base plate; b, the base forming part of the side and end plates; c is the top plate; and d, the side plate.

The ornamental character or design formed on each of the above members, and such as I wish to include in my claim is represented by the drawings, and will be clearly comprehended by any stove pattern maker of ordinary skill.

I would remark that what I claim is the general ornamental design of the stove, as shown in the side and front plates c, d, and I, including the legs, and as represented in the accompanying drawings; and separately, I claim the ornamental design of the oven door E;

2

Nes.

605

that of each of the front doors A, B; that of the door C; that of the door E, & that of the panel B.

In testimony whereof, I have hereto set my signature, this sixteenth day of September, A. D., 1853.

Witnesses,

Wm. Willis,

Thomas Norton.

}

N. P. Richardson.

Ex

J. F. R.